SMITH & WINEGAR.

MACHINE FOR MAKING DRAIN TILES.

No. 26,793.

Patented Jan. 10, 1860.

Fig. 2.

UNITED STATES PATENT OFFICE.

CALEB WINEGAR AND SAMUEL M. SMITH, OF UNION SPRINGS, NEW YORK.

DRAIN-TILE MACHINE.

Specification of Letters Patent No. 26,793, dated January 10, 1860.

To all whom it may concern:

Be it known that we, CALEB WINEGAR and SAMUEL M. SMITH, of Union Springs, in the county of Cayuga and State of New 5 York, have invented a new and useful Improvement in Machines for Making Drain-Tiles; and we do hereby declare that the following is a full, clear, and exact description of the same, reference being had to the 10 accompanying drawings, forming a part of this specification, in which—

Figure 1, is a vertical longitudinal section of the same. Fig. 2, is a horizontal section in the line y, y , in Fig. 2, and Fig. 3, 15 is an end view.

Similar letters of reference, in each of the several figures, indicate corresponding parts.

The nature of our invention consists in 20 the relative arrangement for united operation of the screening box, tile making box, screening plunger, tile plunger, eccentrics for operating said plungers, pulverizing chamber and feeding shaft, substantially 25 in the manner and for the purpose hereinafter described.

With this arrangement, the operations of 30 pulverizing, screening and molding the clay into tiles are performed in one machine and by a continuous revolution of the driving shaft; the pulverizing occurring first, the screening second and the molding third. The 35 pulverized clay empties into the screening box, from thence is forced through the screens into the molding box and from thence forced through the tile molds; the arrangement being such that while clay is being screened at one end of the machine, pulverized clay is coming into the screening 40 box at the other end, and screened clay is being forced out through the tile molds. Thus the machine is caused to work harmoniously and perfectly, although the revolution of the driving shaft is continuous.

45 To enable others, skilled in the art, to make and use our invention, we will proceed to describe its construction and operation.

A, represents the clay pulverizing chamber, B, the screening chamber and C, the 50 tile molding chamber constructed as shown

and arranged one above the other as shown. The chamber A, has passages a, a' , leading into the chamber B. Passages b, b' , are formed in the top of chamber C, for a purpose presently described.

55 Through the three chambers, a central shaft D, passes as shown. This shaft has pulverizing and feeding wings c, c , on that part which comes within the chamber A, and eccentrics d, e , on those parts which 60 come within the chambers B, C, said chambers having slots d', e' , in their sides to allow the eccentrics free play.

E, E', are screens arranged at each end 65 of the chamber B. The outside of these screens just comes even with the inner side of the passages b, b' , of the chamber A, so as to discharge the screened clay into said chamber.

F, G, are box shaped plungers closed at 70 end and fitted by means of oblong slots f, g , in their top, loosely on the shaft D, as shown. These plungers encompass the eccentrics d, e , and have a contact with the circumferences of the same through friction 75 rollers h, i , when the machine is in motion.

H, H, are the tile molds formed in the ends of the chamber C.

From the above description of parts, it 80 will be seen that when the shaft D, is set in motion, the clay in chamber A, will be pulverized and forced down through the opening a into the chamber B, at one end, and as the motion continues, the clay thus forced down will be forced out by the plunger F, 85 through the screen E, into the chamber C, through the passage b . Now as the motion continues, the parts will change their position and while fresh clay is coming into the chamber B, at the opening a' and is being 90 forced out through the screen E' into the other end of chamber C, through the opening b' , the screened clay is being forced out through the tile molds, and thus converted into tiles of a perfect character. Thus the 95 operation continues the whole day, the respective ends of the machine alternately receiving, screening and molding.

We are aware that the several devices we employ have heretofore been applied to 10

brick and tile machines, but not so arranged as to operate jointly in the manner we have devised.

Therefore what we claim as our invention and desire to secure by Letters Patent, is—

The relative arrangement for united operation of the screening box B, tile making box C, screening plunger F, tile plunger G, eccentrics d, e, for operating said plungers

F, G, pulverizing chamber A, and feeding 10 shaft D, substantially as and for the purposes set forth.

CALEB WINEGAR.
SAMUEL M. SMITH.
